R. H. NORTON AND W. C. FORK.
BOX STRAP SEALING IMPLEMENT.
APPLICATION FILED JAN. 6, 1919.

1,322,723.

Patented Nov. 25, 1919.

UNITED STATES PATENT OFFICE.

RALPH H. NORTON AND WILLIAM C. FORK, OF CHICAGO, ILLINOIS, ASSIGNEES TO ACME STEEL GOODS COMPANY, OF CHICAGO, ILLINOIS, A CORPORATION OF ILLINOIS.

BOX-STRAP-SEALING IMPLEMENT.

1,322,723.

Specification of Letters Patent. Patented Nov. 25, 1919.

Application filed January 6, 1919. Serial No. 269,942.

To all whom it may concern:

Be it known that we, RALPH H. NORTON and WILLIAM C. FORK, citizens of the United States, residing at Chicago, in the county of Cook and State of Illinois, have invented certain new and useful Improvements in Box-Strap-Sealing Implements, of which the following is a specification.

Our invention relates to a hand implement for applying a box strap seal of the kind disclosed in the Norton Patent 1,260,016 dated March 19, 1918. The object is to provide an implement of simple construction which can be readily and effectively manipulated to completely and uniformly create such a seal as that of said patent, a characteristic feature of which is the shearing of the marginal portion of the sleeve and the inclosed over-lapped strap ends so that by reason of the incidental deflection of cut or sheared edges, the parts constituting the seal are definitely and positively interlocked against pulling apart.

In the drawings which accompany and form part of this specification, Figure 1 represents the complete instrument in side elevation; Fig. 2 represents the same in longitudinal vertical section; Fig. 3 is a front elevation; Figs. 4 and 5 are front and bottom views of one of the dies; Fig. 6 is a plan view of the other die, or it may be considered as a horizontal section taken substantially on the line 6—6 of Fig. 2; Fig. 7 shows the completed seal in top plan view; Fig. 8 is a broken perspective of the same.

The reference numeral 2 designates a main body portion or base of the implement, which is of bifurcated form for the accommodation of the movable die and also for the mounting of an operating lever 3. The base 2 has a rearwardly extending leg 2^a, somewhat arched, and terminating in a foot 2^b. The stationary one of the dies is, in its general form, a flat plate 4 of hardened metal which is fastened to the under-side of the main body portion 2. This is conveniently done by the use of screws 5 and the die-formation, presently to be described, aids in securely positioning the plate. The latter protrudes slightly beyond the front face of the body 2 and is beveled as shown for the purpose of facilitating its insertion

under the over-lapped strap ends as they over-lie the surface of the box being strapped. (It will be understood that an implement such as that disclosed in the Norton and MacKenzie Patent 1,242,026 is employed to stretch the strap around the box and hold the ends while the sealing is in progress, the said implement being so constructed as to provide ample space to work the sealing implement.) The aforesaid die plate 4 is of reduced thickness in general at its forward portion so that a mouth 6 will be formed between it and the under-side of the body 2, the over-lapped strap ends and the surrounding sleeve being received in that mouth and gaged in lateral position by coming up against its vertical shoulder at the rear. There is an up-standing rib 7 formed centrally of the die plate 4 and extending from front to rear thereof with recesses 8 on opposite sides having sloping bottoms. The formation is well illustrated in Figs. 3 and 6, and it will be observed that the top face of the plate is slightly depressed adjacent the recesses and for a distance toward the opposite side of the plate, the latter having marginal portions 9 flush with the rib. The rib and recess formation is preferably continued all the way through to the rear of the plate, and the underside of the body 2 complementally formed, merely for the purpose of a mortise-and-tenon fit which will insure the correct positioning of the die-plate and a rigid uniting of it with the body portion 2.

When the overlapped strap ends and the surrounding sleeve occupy the mouth 6, the sleeve will be centrally positioned as indicated by dotted lines in Fig. 6, so that its middle transverse portion will rest upon the rib 7, while the strap ends rest, respectively, upon the marginal portions 9 of the die-plate 4.

The movable die is in the form of a block 10 which fits between the side walls of the bifurcated portion of the body 2 and against a back wall thereof, and this block is confined by a plate 11 screwed against the front of the body in a recessed portion thereof. From the bottom face of this block there protrude a series of four cutting and bending projections 10^b. They are integral with

the block 10 but considering their form irrespective of this, they are tetrahedrons. Each of them has two side faces at right angles to the bottom face of the block and at right angles to each other, and a third oblique face. They are located with straight faces confronting each other and spaced apart to correspond with the lateral dimensions of the rib 7 of the die plate 4. Considering these projections as constituted of two pairs on opposite sides of this space, each such pair presents flaring jaws with cutting edges created by the oblique faces and adapted when passing down alongside the rib 7, to shear the metal of the sleeve C and the enveloped strap ends A and B with the effect illustrated by Figs. 7 and 8, which substantially duplicate Figs. 1 and 5 of said Norton patent. As this shearing of the marginal portions of the sleeve and strap ends takes place, the oblique or beveled faces of the die projections operate to deflect the metal on opposite sides of the central transverse area which overlies and rests upon the die rib 7.

25 The upper portion of the block 10 is bifurcated to accommodate an antifriction roller 12 journaled upon a stud which is suitably secured in the arms of the block. The operating lever 3 has a reduced portion which fits between the arms of the body 2 and is pivoted upon a stud 13 carried by said arms. This reduced portion of the lever is of bifurcated form and contains a piece of hardened metal 14. The die block 35 10 is held up by a stiff spring 15, fastened at one end to a lug of the leg 2^a by a screw 17 and entering a hole 10^a of the die block at its free end, as clearly shown in Fig. 2. The roller 12 is in alignment with the metal 40 piece 14 and the latter has in the forward portion of its under edge, a notch or socket 14^a in which said roller seats, the engagement being enforced by said spring 15. This condition is illustrated in Fig. 2 and it will 45 be seen that the die block 10 is so far retracted in its guide-ways that the cutting projections are almost entirely withdrawn from the mouth 6, leaving the latter free to receive the seal assemblage. The engagement 50 of the roller with the said notch or socket furthermore constrains the operating lever 3 to occupy its upright or idle position. It may be noted in this connection that the piece 14 projects downward a sufficient extent in front of the roller to prevent the throwing of the lever forwardly beyond this idle position, to any appreciable extent.

The first effect of forcibly swinging the lever 3 rearward is to unseat the roller 12 60 from the notch or socket 14^a and force the die-block 10 downward, putting the cutting projections in position to act upon the metal of the seal. In the further rearward and downward swinging of the lever the rear 65 portion of the edge of the piece 14 acts with

a camming effect upon the roller 12 to force the block 10 farther down and cause the shearing and bending as before described.

The dimensions of the die-jaws are such, in relation to the dimensions of the assembled seal parts, that the initial downward thrust of the die block 10 (caused by the unseating of the roller 12 and therefore relatively abrupt) does not cause the dies to operate upon the metal, but only to descend on 70 opposite sides of the die-rib 7 into close proximity to the seal parts. It is then the relatively gradual descent of the block (caused by the camming action of the rearward edge of the piece 14 upon the roller 12) which 75 causes the dies to shear the metal and deflect it, under conditions manifestly insuring effective action in this regard. During this operation the central transverse portion of the seal sleeve is firmly supported by the die-rib 7 so that its flatness is preserved, and the seal parts beyond the recesses 8 rest over the top surfaces of the plate 4, so that the seal will emerge in the shape shown in 80 said Norton patent, and in Figs. 7 and 8 90 hereof.

We claim:

1. An implement of the character described comprising a base having a die member with a recessed portion and immediately adjacent flat surfaces; an overhanging head attached to the base,—space being provided for the lateral ingress and egress of assembled strap-ends and sleeve; a die member movable across said space and having cutting side-edges in shearing relationship to edges of the other die member at the latter's recessed portion; and means for applying power to force the one die member upon the assembled strap ends and sleeve; 95 laid crosswise over the recessed portion and flat surfaces of the other die member whereby incisions are made through the metal of the sleeve and strap-ends and limited portions thereof to one side of the incisions are deflected into the recessed portion of the one die member while portions to the other side are sustained by the flat surfaces of said die member and middle uniting portions are also kept flat so that, except for 100 the limited portions deflected by the other die member, the flatness of the seal thus formed is preserved throughout.

2. An implement of the character described comprising a base having a die member with a central rib and recesses on opposite sides thereof and flat surfaces adjacent said recesses; an overhanging head attached to the base,—space being provided for the lateral ingress and egress of assembled 105 strap-ends and sleeve; a die member movable across said space and having cutting edges spaced apart to straddle said rib in shearing relationship to the edges thereof; and means for applying power to force the 110 115 120 125 130

one die member upon the assembled strap-
ends and sleeve laid crosswise over the rib
and recesses and flat surfaces of the other
die member whereby incisions are made
5 through the metal of the said assembly and
limited portions thereof to one side of the
incisions are deflected into the recesses while
the middle transverse area overlying the rib

is kept flat as are likewise those areas over-
lying the aforesaid flat surfaces adjacent 10
the recesses, so that, except for the limited
deflected portions, the flatness of the seal
thus formed is preserved throughout.
